UNITED STATES PATENT OFFICE.

ROBERT CORNELY, OF PARIS, FRANCE.

SEWING-MACHINE.

1,223,564.

Specification of Letters Patent.

Patented Apr. 24, 1917.

Application filed August 13, 1914. Serial No. 856,608.

To all whom it may concern:

Be it known that I, ROBERT CORNELY, a citizen of the United States of America, and a resident of Paris, France, have invented a 5 new and useful Improvement in Sewing-Machines, which is fully set forth in the following specification.

The present invention relates to sewing, hemstitching, embroidering and like machines working with several needles and has 10 for its object to enable these machines to produce seams or embroideries of different widths.

In the drawings the invention has been 15 shown in combination with a hemstitching machine but as explained in the course of the present specification, the invention can just as well be used in combination with any kind of multiple needle sewing or embroidering machine.

Hemstitch seams are produced in the well known manner by the coöperation of two periodically spreading needles with a piercer which pierces the material.

25 The width of the hemstitch seam or embroidery depends not only on the amplitude of the oscillations of the needles, but also on the distance at which the needles perform their oscillations from each other, 30 this latter distance will in the present description be called for more simplicity the distance between the two inner rows of stitches.

In order to permit one and the same machine 35 to produce seams of different widths, it is therefore necessary to regulate not only the amplitude of the oscillations of the needles, but also the distance between the two inner rows of stitches.

40 In some of the machines known heretofore this latter regulating of the distance between the two inner rows of stitches was obtained by regulating devices located either on a lever which causes the spreading of the 45 needles (U. S. P. No. 988,050) or between said lever and the needle spreading device according to U. S. P. No. 1,090,136, while on the contrary in the present invention both regulations are obtained by the adjustment of one and the same lever which 50 actuates the lateral displacements of the needles by which a far simpler and more reliable regulation is obtained.

The drawings represent by way of example 55 only a hemstitching machine in which the lateral displacements of the needles are

caused by any one of the known means such as for instance as shown and described in United States Patents No. 988,050 and 1,090,136, but the invention may be used in 60 combination with any other needle spreading devices.

Figure 1 is a view in elevation showing a hemstitching sewing machine provided with my improvements;

Fig. 2 is a broken detail view showing the manner of adjusting the lever 10;

Fig. 3 is a view in elevation showing one form of needle oscillating means;

Fig. 4 is a view in elevation showing another form of needle oscillating means;

Figs. 5, 6 and 7 are enlarged views of lever 10 in different positions of adjustment, and

Figs. 8 and 9 are detailed views of the 75 shuttle or hook holder brackets.

Main shaft 1 of the machine is provided in the well known manner with a tooth wheel 2 which drives a three times larger wheel 3, the latter rotates shaft 4 together 80 with cam 5 which causes the bell crank lever 7 to oscillate upon its pivot 6. The lower arm of said lever 7 is provided with a slot 8 into which engages a movable bolt 9 which at the same time engages also in a 85 corresponding slot of lever 10 which oscillates upon pivot 11 in order to transmit by means of pivot 16 an up and down motion to slide 13 which moves the oscillating device of the needles such as for instance 90 shown in Fig. 1 (according to U. S. P. No. 1,090,136) or as shown in Fig. 1 (according to U. S. P. No. 988,050) which need not to be explained here again in all their details.

The regulating of the amplitude of the oscillations of the needles is also obtained by the means shown and described in the above cited Letters Patent by means of the displacement of bolt or pivot 9 within slots 8 of levers 7 and 10.

But in the present invention the regulating or adjusting the distance between the two inner rows of stitches is obtained in the following manner:

The position of pivot 11 upon which the 105 lever 10 oscillates has been rendered adjustable and for this purpose it is for instance formed eccentrically with regard to its rear part 12 (Fig. 2) which can be turned within its bracket.

In Figs. 5, 6 and 7 this lever 10 and its pivot 11 are represented on a large scale,

Fig. 6 corresponds with the medium position of lever 10 of Fig. 1 in which the centers 14 and 15 of the two cylindrical shafts 11 and 12 are both upon the horizontal line

of each other and are connected slidably to the table plate 33 of the machine in any suitable manner such for instance as shown at Figs. 8 and 9.

It is therefore clear that by means of this arrangement the shuttles, hooks or like will follow automatically all lateral displacements of the needles.

The shuttles, hooks or like 34 and 35 may be actuated by any of the known means in sewing machines, such as for instance from shaft 36 by means of cog wheels 37, 38, 39 and 40 but in this case cog wheels 37 and 38 must also be slidable upon shaft 36 so that they will follow the displacements of brackets 29 and 30 and for this purpose said brackets 29 and 30 are provided each with a fork 41 and 42 which engages a groove of wheels 37 and 38, while shaft 36 is also provided with a groove into which engage corresponding keys on wheels 37 and 38 which can thus follow the displacements of brackets 29 and 30 while they are rotated by shaft 36.

It is therefore clear that for regulating the machine for producing a determined width of seam it is sufficient to adjust the pivots 9 and 11 of lever 10 so that simultaneously and automatically the shuttles, hooks or like are regulated not only into the right positions corresponding with the distance between the two inner rows of stitches, but follow also the oscillations of the needles, so that in all positions of the needles the formation of the seams will take place correctly.

In the example shown in the drawing the up and down motion of the needle-bars 43 and 44 is actuated by any one of the means used in sewing machines, such as for instance by a crank pin of main shaft 1 which by means of a pitman 45 transmits an up and down movement to bar 46 at the lower end of which are pivoted at 47 and 48 the needle bars 43 and 44, while the take-up for the needle threads is moved by cam 49.

The piercer which works between the needles may be actuated by cam 50 of main shaft 1 as shown and described in Letters Patent No. 1,090,136.

What I claim is:

1. In a sewing machine, the combination of vertically reciprocating needle bars, needle separating and needle oscillating means including a lever having a crank pin support, the movement of which support effects simultaneous adjustment of the separating and oscillating means to produce seams of different widths.

2. In a sewing machine, the combination of vertically reciprocating needle bars, needle separating and needle oscillating means including a lever having a crank pin support, the movement of which support effects simultaneous adjustment of the separating and oscillating means to produce seams of

A—B. But when as shown at Fig. 5, the center 15 of pivot or eccentric 11 is displaced downward around center 14 of shaft 12, then the connecting point 16 of lever 10 with slide 13 will be adjusted in a lower position (according to dotted line C—D) thus lowering the position of slide 13 by which, according to the above cited Letters Patent, the distance between the two inner rows of seams will be increased.

15. The contrary will take place when according to Fig. 7 shaft 11 is turned upward. This adjustment can be obtained with the greatest precision by providing shaft 12 with a sector 17 which bears divisions 18 and a slot 19 through which engages a screw 20 which is to be tightened after the adjustment has been made.

20. It is therefore clear that both adjustments, the one of the amplitude of the oscillations of the needles and the one of the distance between the two inner rows of stitches are obtained directly by the adjustments of the one and same lever 10 without making use of any other regulating device located upon said lever or between said lever and the needle spreading device.

25. Although the example represented in the drawings shows the invention in combination with a hemstitch sewing machine only, it is evident that the same invention can be used just as well in combination with a hemstitch embroidering machine.

30. When variations in the width of the seam are to be performed, certain of these machines, when for instance working with rotating shuttles, hooks or like, require that the positions of said shuttles or like correspond exactly with the positions of the needles for a correct formation of the seams or embroideries.

35. This regulating of the positions of the shuttles, hooks or like in conformity with the positions of the needles is in the present invention also obtained by the one and same above described lever 10 on account of its swinging upon a pivot which is adjustable in its position and this is obtained in the following manner:

40. At the other end of lever 10 is pivoted at 21 a rod 22 which by means of pivot 24 oscillates a double armed lever 23 which oscillates at 25 upon bracket 26 and thus transmits a to and fro motion to rods 27 and 28 but in opposite directions to each other, so that when rod 27 moves to the right, rod 28 moves to the left and vice versa. These two rods 27 and 28 are pivoted at 31 and 32 to the shuttle or hook holder 45 brackets 29 and 30 which are independent

different widths, and a graduated sector adapted to lock said crank pin support in a predetermined position.

3. In a sewing machine, the combination
5 of vertically reciprocating needle bars, needle separating and needle oscillating means including a lever having a crank pin support, and shuttle mechanism having connection with said lever, the movement of said
10 lever support effecting simultaneously the

adjustment of the separating and oscillating means and of the shuttle mechanism.

In testimony whereof I have signed this specification in the presence of two subscribing witnesses.

ROBERT CORNELY.
